[57] CLAIM

[21] Appl. No.: 655,932

The ornamental design for a interior burglar bars with
fire exit, as shown and described.

[22] Filed: Feb. 15, 1991

DESCRIPTION

[52] U.S. Cl. D25/53

FIG. 1 is a front elevational view of the interior burglar
bars with fire exit showing my new design;
FIG. 2 is a rear elevational view thereof;
FIG. 3 is a left side elevational view thereof;
FIG. 4 is a right side elevational view thereof;
FIG. 5 is a top plan view thereof;
FIG. 6 is a bottom plan view thereof; and,
FIG. 7 is a perspective view thereof, the broken lines
showing a lock are for illustrative purposes only and
form no part of the claimed design.[58] Field of Search D25/53, 48, 142, 143,
D25/152, 156; 49/50, 52, 56; 52/106, 507, 660,
663, 665, 26
